US0D1062122S

(12) **United States Design Patent** (10) Patent No.: **US D1,062,122 S**
(45) Date of Patent: ** Feb. 11, 2025

(54) **FILTER FOR FILTERING AGITATOR**

(71) Applicant: **WHIRLPOOL CORPORATION**,
Benton Harbor, MI (US)

(72) Inventors: **Seth E. Bixby**, Stevensville, MI (US);
Chloe P. Condon, St. Joseph, MI (US);
James D. Jeffery, St. Joseph, MI (US);
Sayer J. Murphy, St. Joseph, MI (US);
Jonathan D. Pugh, Benton Harbor, MI (US);
Ryan J. Rutter, St. Joseph, MI (US);
Eric J. Vasko, St. Joseph, MI (US);
David Walter, III, St. Joseph, MI (US)

(73) Assignee: **WHIRLPOOL CORPORATION**,
Benton Harbor, MI (US)

(**) Term: **15 Years**

(21) Appl. No.: **29/836,362**

(22) Filed: **Apr. 26, 2022**

(51) LOC (15) Cl. **15-05**

(52) U.S. Cl.

USPC **D32/26**

(58) **Field of Classification Search**
